INVENTOR

Rector Egeland.

UNITED STATES PATENT OFFICE.

RECTOR EGELAND, OF CHICAGO, ILLINOIS.

TUBE AND HINGE FOR LOOSE-LEAF BINDERS.

Application filed March 16, 1925. Serial No. 15,908.

To all whom it may concern:

Be it known that I, RECTOR EGELAND, a citizen of the United States, and a resident of the city of Chicago, in the county of Cook 5 and State of Illinois, have invented certain new and useful Improvements in a Tube and Hinge for Loose-Leaf Binders; and I do hereby declare that the following is a full, clear, and exact description of the same, 10 reference being had to the accompanying drawings, and to the numerals of reference marked thereon, which form a part of this specification.

This invention relates to, improvements in 15 loose leaf sectional or solid post binders, of the metal or piano hinged type and has among its various objects the construction of a metal hinged post binder, which can be manufactured cheaply and will withstand 20 the rough usage required of metal hinged binders.

It has been found by manufacturers that the piano hinged binder is the most durable loose leaf binder that can be made for universal use, but the cost of its manufacture makes the common use of such binders prohibitive.

It has therefore been the object of the inventor to design a binder which will have 30 all the desirable features embodied in a piano hinged binder but whose cost of material and manufacture would be appreciably lowered by elimination of waste in metal, covering material and labor.

The primary object of my invention is to 35 provide a loose hinge eye which is inserted in a slot in ends of each metal tube whereby said hinge eye can be inserted in ends of tubes after said tubes have been bound or covered, said hinge eye to be held rigidly in place by a metal end cap or plug and by slot cut in hinge eye, said hinge eye to coincide or fit with cover hinge eye and to be held in place by inserting rod through hinge 45 eyes or metals and covers.

In the accompanying drawings which illustrate a preferred embodiment of this invention and in which similar reference numerals refer to same features in the different views:

Figure 1 is a top plan view of a binder involving this invention.

Figure 2 is an enlarged plan view of one of the tubular clamping members.

Figure 3 is an enlarged sectional view upon line 3—3 of Figure 2.

Figure 4 is a perspective view of one of the bearings or loose hinge eye members.

Figure 5 is an enlarged sectional view upon line 5—5 in Figure 3.

The binder as illustrated, to which my invention applies consists of a pair of covers 1 having clamping members 2 hinged to the binding edges thereof; one of these clamping members has a pair of posts which are 65 adapted to be adjustably locked in apertures in the other clamping member.

Each clamping member 2 is formed from a rectangular sheet of metal which is bent into a flat tubular form, the edges being 70 brought together on the side opposite from that in which I propose to cut a slot for the insertion of the hinge eye as shown in Figure 3.

The hinge eyes or bearings 4 are separately formed from a rectangular piece of metal which is bent to provide the eye or bearing 4^a with oppositely extending flanges 4^b shaped to fit the flat tubular form 2 as illustrated in Figure 3. These hinge eyes 80 or bearings are slotted in the flanges as shown in Figure 4 indicated as 4^c to prevent any vertical motion as shown in the sectional view Figure 5.

Figures 3 and 5 show clearly how the 85 hinge eye or bearing is inserted in the slot of the tubular metal and held rigidly in place by the slot 4^a and the metal end cap or plug 6 which is given a tight friction fit.

It is of course, easily understood, that the 90 hinge eyes or bearings serve to hinge the covers to the clamping members by means of a rod as is well known to the trade.

The operations as outlined above can be completed after the covers and clamping 95 members have been covered and finished by the binder, making the work to complete same a simple assembling operation.

The foregoing detailed description has been given for clearness of understanding 100 and no unnecessary limitations should be understood therefrom; but the claims should be construed as broadly as permissible in view of the prior art.

What I regard as new, and desire to secure by Letters Patent, is:—

1. In a loose leaf binder, a hollow clamping member formed from a rectangular piece of metal with a slot cut in the side opposite to its meeting edges, a hinge eye or bearing with a cylindrical portion, a web portion to fit said slot in clamping member, two flanges 110

to fit inner surface of clamping member and a metal end plug or cap to hold hinge eye rigidly in place.

2. A clamping member for a loose leaf binder consisting of a flat tubular metal member having a slot cut in each end in the side opposite the meeting edges, hinge eyes or bearings, each having a cylindrical portion, a web portion to fit said slots in clamping member, two flanges to fit inner surface of clamping member and metal end caps or plugs to hold hinge eyes rigidly in place.

3. A hinge eye or bearing for a slotted tubular clamping member formed from a rectangular piece of metal with a cylindrical portion in said hinge eye to receive a hinge rod, a web portion to fit slot in clamping member and a longitudinal notch in said web portion to fit tubular metal member and

extend beyond slotted portion of said tubular metal member to prevent vertical motion, and two flanges to fit inner surface of tubular clamping member.

4. A clamping member for a loose leaf binder with rectangular slots in each end in the side opposite the meeting edges of said clamping member for inserting hinge eyes, each having a cylindrical portion a web portion with a longitudinal slot in said web portion to prevent vertical motion, two flanges shaped to fit inner surface of clamping member and metal end caps or plugs to hold said hinge eyes in place to form a rigid hinged clamping member connection for a loose leaf binder.

In testimony whereof I affix my signature.

RECTOR EGELAND.
